[57] **CLAIM**

The ornamental design for a tool, as shown and described.

DESCRIPTION

FIG. 1 is a front elevational view of a tool showing my new design;

FIG. 2 is a rear elevational view thereof;

FIG. 3 is a top plan view thereof;

FIG. 4 is a bottom plan view thereof;

FIG. 5 is a right side elevational view thereof, wherein the left side view is a mirror image;

FIG. 6 is a left front perspective view thereof;

FIG. 7 is a perspective view thereof, wherein the broken line showings of the bits are for illustrative purposes only and form no part of the claimed design; and,

FIG. 8 is a perspective view thereof, showing the tool in a closed position, wherein the broken line showing of the bit is for illustrative purposes only and forms no part of the claimed design.
